UNITED STATES PATENT OFFICE.

GEORGE HERBERT DORMER, OF EVELETH, MINNESOTA.

DETONATING BLASTING-FUSE.

1,275,001.

Specification of Letters Patent. Patented Aug. 6, 1918.

Application filed November 27, 1917. Serial No. 904,180.

To all whom it may concern:

Be it known that I, GEORGE HERBERT DORMER, a citizen of the United States, and a resident of Eveleth, in the county of St. Louis and State of Minnesota, have invented a new and Improved Detonating Blasting-Fuse, of which the following is a full, clear, and exact description.

My invention relates to burning fuses utilized for blasting purposes. An object of the invention is to provide a fuse which has means at suitable intervals in the body of same adapted to produce a detonation which serves as a warning of a proximate explosion to be caused by the burning of a fuse.

With the above and other objects in view, the nature of which will more fully appear as the description proceeds, the invention consists in the novel construction, combination and arrangement of parts as herein fully described, illustrated and claimed.

In the accompanying drawings, forming part of the application, similar characters of reference indicate corresponding parts in both views.

Figure 1 is an elevation of a segment of a fuse embodying my invention; and

Fig. 2 is a longitudinal section through same.

A great many lives are lost every year, and many permanently injured, by premature explosions, due in some cases to too rapid burning of the fuse but more often to the very poor conception the average person has of the period of time in one and

one-half minutes. This is the time it takes a standard make of fuse to burn three feet, the length most generally used. To obviate such accidents, I provide a fuse which has 40 at intervals of three feet a detonating section 3. The charge of detonating material is such that the detonation is distinct to give warning and may be made similar to a large firecracker. It is incorporated in the 45 core 4 of the fuse and protected from the effect of the atmosphere by the material which houses the core.

Generally the detonating section will be placed one foot from the cap which sets 50 off the charge, therefore there will be two feet of fuse ahead of the detonating section, and in consequence when the detonating section 3 explodes it will give warning that the charge is going to be fired in one-half min- 55 ute, or that the fire in the fuse is within one foot of the cap which will set off the charge.

The warning caused by the explosion of the detonating section 3 will give notice of the shortest length of time one has to reach 60 a place of safety.

I claim:

1. As an article of manufacture, a burning blasting fuse having detonating sections therein at suitable intervals adapted to serve 65 as a warning of the proximate explosion of the blast.

2. As an article of manufacture, a burning fuse for blasting purposes having detonating sections at intervals of about three 70 feet.

GEORGE HERBERT DORMER.
